Primary Examiner — Elizabeth J Oswecki(74) Attorney, Agent, or Firm — R. Keith Harrison(57) CLAIM

The ornamental design for a lighted cross, as shown and described.

DESCRIPTION

FIG. 1 is a front perspective view of a lighted cross showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

In the drawings, the broken lines in FIGS. 1-6 depict portions of the design that form no part of the claimed design.
